CLAIM

We claim the ornamental design for a door with refrigerator and delivery storage box, as shown and described.

DESCRIPTION

FIG. 1 is a perspective view of a door with refrigerator and delivery storage box showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view showing a state of the delivery storage opened; and,

FIG. 9 is a perspective view showing a state of the refrigerator opened.

The broken lines shown in FIG. 3 depict portions of the door with refrigerator and delivery storage box that form no part of the claimed design.
